UNITED STATES PATENT OFFICE.

WILMER THOMAS PITTMAN, OF HAMPTON, VIRGINIA.

DESIGN FOR A VEHICLE LAMP CASING OR ARTICLE OF SIMILAR NATURE.

Application filed March 28, 1927. Serial No. 21,373. Term of patent 14 years.

To all whom it may concern:

Be it known that I, WILMER THOMAS PITTMAN, a citizen of the United States, residing at Hampton, in the county of Elizabeth City and State of Virginia, have invented a new, original, and ornamental Design for Vehicle Lamp Casing or Article of Similar Nature, of which the following is a specification, reference being had to the accompanying drawing, forming a part thereof.

I claim:

An ornamental design for a vehicle lamp casing or article of similar nature, as shown.

March 28, 1927.

WILMER THOMAS PITTMAN.
